Primary Examiner — Richard E Chilcot

(57) **CLAIM**

The ornamental design for a solar-powered fence lamp, as shown and described.

DESCRIPTION

FIG. 1 is a perspective view of a solar-powered fence lamp showing our new design;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof;

FIG. 8 is an enlarged view of the encircled area 8 in FIG. 3; and,

FIG. 9 is an enlarged view of the encircled area 9 in FIG. 3.

The broken lines shown on the drawings depict portions of the solar-powered fence lamp that form no part of the claimed design. The dot dash lines shown in FIGS. 8 and 9 show boundaries of enlarged portions of FIG. 3 and form no part of the claimed design.

1 Claim, 9 Drawing Sheets
